UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

TANDEM ALLOTTING SYSTEM.

Application filed May 21, 1919. Serial No. 298,580.

To all whom it may concern:

Be it known that I, ALBEN E. LUNDELL, a citizen of the United States, residing at New York, in the county of Bronx and State of New York, have invented certain new and useful Improvements in Tandem Allotting Systems, of which the following is a full, clear, concise, and exact description.

This invention relates to automatic telephone exchange systems and more particularly to the distribution of apparatus in such systems.

In telephone systems employing the finder switches it has been customary to provide an allotting switch for each group of line finders, the function of this allotting switch being to prepare a finder switch for operation, and as soon as such allotted finder switch is taken for use to hunt out another idle finder switch and prepare it for operation. A defect of this arrangement is due to the fact that the group of finders controlled by an allotter is necessarily small, since, if a large number of switches are controlled by a single allotter, considerable time might be needed before the allotter could pick out an idle one in case many of the intervening switches were busy. During this time interval it might be possible that several calls would be originated.

If, now, it is desired to utilize a 500 point switch as a line finder, and distribution is to be on a 10% basis, 50 line finders would have to be provided to serve this group. The allotter would then have to hunt over a possible 50 contacts and might frequently have to pass over a considerable number before finding an idle one. The time required for this would be, as pointed out above, an undesirable feature.

It is the object of this invention to provide an arrangement in which a large number of finder switches are commonly available to the subscribers of a group and in which there is never more than one finder in a position to be started at any given time. The object of the invention has been set forth in connection with line finder switches and the following specification will explain the operation of a system embodying this type of switch, but it is obvious that the principle involved is capable of adaptation to a large variety of switches whose functions may be of various characters. The in-

vention is, therefore, not to be restricted except as to the subject matter set forth in the claims.

A feature of the invention is the provision of a tandem arrangement of allotter switches, there being a central, or master allotter switch, as it will be termed hereinafter, which is individual to a main group of line finders. In addition to this master allotter switch there will be an allotter switch individual to each smaller group of finders into which the main group is divided. The arrangement is such that the allotting of any given finder is the result of the joint operation of the master allotter, and the allotter individual to some one of the smaller groups.

An additional feature of the invention is an arrangement by which the allotters of the smaller groups pre-select an idle finder, so that as soon as the master allotter moves into connection with this sub-group allotter, the sequence switch associated with the finder will be advanced.

A further feature of the invention resides in the provision of means whereby the master allotter will not stop when it comes into operative relation with a group allotter in whose group there are no idle finders.

A still further feature of the invention is provided by an arrangement such that the master allotter moves from sub-group to sub-group after each allotting operation, thus producing a system in which every finder has an equal chance of being brought into use. This proves a decided advantage over a system in which certain of the devices are brought into use repeatedly while others do relatively little work.

It is thought that the invention will best be understood from the following detailed description, reference being had to the accompanying drawings.

In the drawings, Fig. 1 diagrammatically indicates a main group of finders, the first finder of the first group being provided with operating circuits, while the other finders have only certain portions of their operating circuits shown.

Fig. 2 shows a master allotter individual to the main group, and group allotters individual to the various smaller groups in such great group. In Fig. 2 the master allotter is shown at the left-hand portion of the

drawing, while the group allotters are provided with designations which will readily identify them.

If we assume that the switch is of 500 line capacity, we may then assume that there are 50 line finders which will serve this group. These 50 line finders will constitute what has been termed a great group. The great group is divided into five smaller groups of 10 line finders each, each one having an allotter associated with it.

The line finder switch shown in Fig. 1 is of the power driven type. In practice this switch would be of the multiple brush type having five normally inoperative brush sets, one of which is rendered operative as a result of a brush selecting operation. Since, however, the invention is not concerned with any particular type of switch, it has been assumed that the line finder shown is provided with only one brush set which is arranged to be advanced in a continuous motion over the entire group of 500 terminals. The mechanical construction of such a switch will be entirely obvious to one skilled in the art when considered in connection with the circuit to be described. In order to prevent the disclosure from becoming unnecessarily complicated, it has been assumed that the line finder is directly connected to a connector switch which will make connection to a called subscriber. This switch has been shown as being a step-by-step switch, and may be of any one of several well-known types of two motion step-by-step automatic switches. A switch of this type is shown in Patent No. 1,252,420 to O. F. Forsberg. The allotter switches are all of similar construction and may preferably be of a mechanical structure similar to that shown in Patent No. 1,127,808, issued to E. B. Craft and J. N. Reynolds. The invention is, however, obviously not limited to the employment of an allotting switch of this type.

The operation of the system is as follows: When the subscriber at substation 1 removes his receiver from the switchhook, a circuit is completed from grounded battery, left-hand winding of line relay 2, outer armature and back contact of cut-off relay 3, over the loop of the calling subscriber's line, inner armature and back contact of relay 3, right-hand winding of relay 2 to ground. Line relay 2 energizes and completes a circuit from grounded battery, power magnet of sequence switch 4, which, it must be understood, was placed into position 1 in readiness for operation, upper contact of sequence switch spring 5, left-hand armature and front contact of relay 2 to ground. Sequence switch 4 under the control of its master contact 6 moves out of position 1 and into position 2.

In position 2 of sequence switch 4, a circuit is completed from grounded battery, winding of up-drive magnet 7, armature and

back contact of test relay 8, contact of sequence switch spring 9 to ground. The finder brushes 10, 11, 12 are moved upwardly over the terminal bank in search of the calling line under the control of magnet 7. When the test brush 10 engages the test contact of the calling line, a circuit is completed from grounded battery, right-hand armature and front contact of relay 2, resistance 14, test brush 10 and its associated contact, lower contact of sequence switch spring 13, winding of relay 8 to ground. If parallel a circuit is completed from grounded battery, winding of cut-off relay 3 to ground as described. Relays 3 and 8 are energized in this circuit, relay 8 at its armature opening the driving circuit of magnet 7, thus bringing the brush set to rest upon the desired terminal. Cut-off relay 3 upon energization removes the control of the calling subscriber's line relay in the well-known manner, and provides a holding circuit for relay 8. Relay 8 is marginal and will not operate while test brush 10 is passing over the terminals of non-calling or busy lines. If these lines are busy as calling lines, a shunting ground is provided by way of resistance 15 of the finder associated with such other line to prevent the operation of relay 8. If busy as called lines, this shunting ground is provided by way of resistances 16, associated with the connectors which have seized such lines. If the line is non-calling, the resistance of cut-off relay 3 is sufficient to prevent the operation of line relay 8, it being necessary that battery be supplied both through the winding of relay 3 and through resistance 14 in parallel in order that relay 8 may be energized. The current flowing through relay 3 is not sufficient to cause the actuation of relay 8, but is sufficient to maintain this relay energized after it has been actuated.

The energization of relay 8 also completes a circuit from grounded battery, power magnet of sequence switch 4, armature and front contact of relay 8, contact of sequence switch spring 9 to ground, for moving this sequence switch out of position 2 and into position 3. When sequence switch 4 reaches position 2½, a grounded shunt path is placed on the test terminal of the calling line to prevent its seizure by other hunting line finders. In position 3 of sequence switch 4, the subscriber's line is connected to the step-by-step connector by way of sequence switch 17 and 18.

A circuit is now completed from grounded battery, left-hand winding of line relay 19, over the upper side of the line to the calling substation, thence by way of the lower side of the line and right-hand winding of relay 19 to ground. Relay 19 is energized and completes a circuit from grounded battery, winding of slow-release relay 20,

armature and front contact of relay 19 to ground. Relay 20 is energized in this circuit.

The calling subscriber now operates his impulse sending mechanism 21 to send the first digit of the calling subscriber's number. Since the finder is directly connected to a 100 point connector switch, it will only be necessary for him to dial the tens and units digits. In response to the operation of the dial, the line circuit is intermittently interrupted, causing in turn the intermittent operation of relay 19. Upon the first de-energization of relay 19, a circuit is completed from grounded battery, winding of slow-release relay 22, armature and front contact of relay 20, armature and back contact of relay 19 to ground. Relay 22 is energized and completes a circuit from grounded battery, power magnet of sequence switch 4, lower right-hand contact of sequence switch spring 23, armature and front contact of relay 22 to ground, for removing the sequence switch out of position 3 and into position 4. Relays 22 and 23 being slow to release, remain energized throughout the series of impulses. At each retraction of the armature of relay 19, a circuit is completed from grounded battery, winding of primary stepping magnet 24, lower contact of sequence switch spring 25, armature and front contact of relay 20, armature and back contact of relay 19 to ground. Upon each energization of magnet 24, the brush shaft of the connector switch is advanced a group step.

Upon the termination of this series of impulses, relay 19 remains energized for a relatively long period, causing the deenergization of relay 22. Relay 22 upon deenergization completes a circuit from grounded battery, power magnet of sequence switch 4, upper contact of sequence switch spring 23, armature and back contact of relay 22 to ground for moving this sequence switch out of position 4 and into position 5.

The subscriber now sends the units series of impulses. As before, the first deenergization of relay 19 causes the energization of relay 22. Relay 22 attracts its armature and advances the sequence switch into position 6 over a circuit identical with that for moving sequence switch 4 from position 3 to position 4. Each retraction of the armature of relay 19 also completes a circuit from grounded battery, winding of secondary stepping magnet 26, upper contact of sequence switch spring 25, armature and front contact of relay 20, armature and back contact of relay 19 to ground. Upon each energization of magnet 26 the brushes 27, 28 and 29 are advanced over a set of terminals in the selected group. Upon the completion of the sending of the second series of impulses, relay 19 remains energized,

causing the deenergization of relay 22, which completes a circuit removing sequence switch 4 out of position 6 and into position 7.

Assuming that the called subscriber's line is idle, a circuit is completed as soon as sequence switch 4 reaches position 7, extending from grounded battery, power magnet of sequence switch 4, lower contact of sequence switch spring 36, left-hand armature and back contact of relay 33, to ground, for moving the sequence switch out of position 7 and into position 8.

In position 8 guarding potential is applied to the test terminal of the called line by way of sequence switch spring 37 and resistance 16. At the same time ringing current is supplied to the called sub-station from a source of alternating current, winding of relay 38, contact of sequence switch spring 39, brush 27, over the upper side of the called line, through the sub-station apparatus, including the bells and condenser, over the lower side of the line, brush 28, contact of sequence spring 40, to ground. When the called subscriber removes his receiver, the current flow through relay 38 is increased sufficiently to allow this relay to attract its armature, thus completing a circuit from grounded battery, power magnet of sequence switch 4, upper right-hand contact of sequence switch spring 41, armature and front contact of relay 38, to ground, for moving this sequence switch out of position 8 and into position 9.

Position 9 is the talking position and the calling line is connected to the called line by way of sequence switch springs 30 and 31. During conversation, battery is supplied to the called line through the windings of a resistance 32. After conversation is completed the calling subscriber replaces his receiver on the switchhook, causing the deenergization of relay 19 which, in turn, causes the release of relay 20. A circuit is now completed from grounded battery, power magnet of sequence switch 4, lower contact of sequence switch spring 41, armatures and back contacts of relays 20 and 19, to ground, for moving the sequence switch out of position 9 and into position 10.

In position 10 a circuit is completed from grounded battery, winding of down-drive magnet 42, contact of sequence switch spring 43, to ground. Under the control of magnet 42 the finder brush set is returned to its normal position. When the commutator brush 44, mounted on the brush carriage, engages the normal commutator segment 45, which occurs when the switch is fully restored, a circuit is completed from grounded battery, power magnet of sequence switch 4, upper left-hand contact of sequence switch spring 41, segment 45, brush 44, to ground, for moving the sequence switch out of position 10.

tion 10 and into position 11. As soon as the sequence switch leaves position 10, the circuit of magnet 42 is opened.

In position 11 of sequence switch 4, a circuit is completed from grounded battery, winding of connector release magnet 46, upper contact of off-normal spring 47, contact of sequence switch spring 48, to ground. The energization of release magnet 46 allows the connector switch to be restored, and when it is fully restored, off-normal spring 47 opens its upper contact and closes its lower contact, whereupon a circuit is completed from grounded battery, winding of power magnet of sequence switch 4, lower left-hand contact of sequence switch spring 23, lower contact of off-normal spring 47, contact of sequence switch spring 48, to ground, for moving the sequence switch 4 out of position 11 and into position 18. The sequence switch remains in position 18 until the finder is reallocated for service.

Assuming now that at the time the brushes 27, 28 and 29 were placed on the terminals of the wanted line this line was busy, a circuit is completed for test relay 33 as soon as sequence switch 4 reaches position 6½. This circuit extends from grounded battery, winding of relay 33, contact of sequence switch spring 35, test brush 29 and its associated contact, and thence to ground by way of sequence switch spring 37 and resistance 16 of the connector which has previously seized such line, provided that the line is busy as a called line. If it is busy as a calling line, the ground for energizing relay 33 will be supplied from the test brush by way of the upper contact of sequence switch spring 13 and resistance 15, associated with the finder which has seized the line. Relay 33 upon energization locks up through its inner right-hand armature until sequence switch 4 leaves position 9. As soon as relay 33 is energized, a circuit is completed for supplying busy tone to the calling subscriber's line. This circuit extends from ground through the secondary winding of an induction coil, the primary circuit of which includes an interrupting device and battery, through the outer right-hand armature of relay 33 and thence over the lower talking conductor, through the calling sub-station apparatus, over the upper side of the line and through the left-hand winding of relay 19, to grounded battery. This tone will inform the calling subscriber that the desired line is busy.

Relay 33, at its left-hand armature, completes a circuit from grounded battery, power magnet of sequence switch 4, upper right contact of sequence switch spring 36, left-hand armature and front contact of relay 33, to ground, for moving this sequence switch through positions 7, 8 and 9 and into

position 10, whereupon the down-drive magnet becomes effective and the release of the finder and connector take place as previously described.

The operation of the allotting system will now be described. It was assumed that at 70 the time the calling subscriber at sub-station 1 initiated a call, the sequence switch of the first finder was in position 1. At this time the allotter of the first group will also be in position 1 and the master allotter will be 75 in position 1.

After the finder is taken for use and its associated sequence switch moves out of position 1, a circuit will be completed for advancing the master allotter when sequence switch 4 reaches position 1½. This circuit extends from grounded battery, winding of power magnet of master allotter 100, upper left-hand contact of allotter spring 101, conductor 102, lower contact of sequence switch spring 50, to ground. The master allotter 100 moves from position 1 to position 2 under the control of its normal controlling spring 103. The master allotter will come to rest in position 2 provided that 90 there is an idle finder in the second group. If all the finders in the second group are busy, a circuit will be completed from grounded battery, power magnet of master allotter 100, the upper right-hand contact of allotter spring 101, conductor 104, through the contacts 105, 106, 107, 108, etc., of the finders of the second group, to ground. In response to the completion of this circuit the master allotter moves on to position 3, at which time it will extend the control circuit to contacts controlled by the allotter individual to the third group.

When the finder whose operation has just been described reaches position 2, a circuit is completed from grounded battery, power magnet of allotter 200, which is individual to the first group of finders, upper left-hand contact of allotter spring 201, conductor 202, contact of sequence switch spring 51, to ground, for moving this allotter out of position 1 in search of another idle finder. The allotter 200 will rotate until a finder whose sequence switch is standing in position 18, is found, due to the fact that the circuit of the upper magnet of allotter 200 is completed by way of a sequence switch spring similar to sequence switch spring 51 on all busy finders, since the sequence switches of busy finders will be in some position included in the positions 2 to 17.

As soon as allotter 200 finds a finder whose sequence switch is in position 18, the allotter comes to rest and the control circuit by way of conductor 203 is extended to such finder. The allotter 200 cannot, however, move this sequence switch to a position wherein the finder may be started, since the control cir-

cuit by way of conductor 203 is not completed until the master allotter arrives in position 1.

All of the group allotters operate as has just been described for allotter 200, that is, they preselect or preallot a finder which is in position to be started and, as soon as the control circuit is extended to them in response to the operation of the master allotter, the control circuit becomes effective to advance such preallotted finder into position to be started.

For instance, when the first finder of the first group is in readiness for reallocation, that is, when its sequence switch is in position 18, allotter 200 may preallot this finder by stopping in position 1.

The finder sequence switch will not be advanced, however, until master allotter 100 reaches position 1, at which time a circuit will be completed from grounded battery, power magnet of sequence switch 4, lower contact of sequence switch spring 5, conductor 70, upper left-hand contact of sequence switch spring 204, conductor 203, upper left-hand contact of master allotter spring 109 to ground, for moving sequence switch 4 out of position 18 and into position 1.

From the foregoing it will appear that the following desirable results are obtained from a system of this character, due to the fact that each one of the five group allotters is a preallotting switch. Any time that there is an available finder switch it can be moved into position to be started as the result of a maximum movement of five steps of the master allotting switch, since if all the finders in the four groups are busy, they will be passed over one by one, as a result of a single step of the master allotter and then the preallotted finder in the fifth group will be seized. In this way a large number of finders may be allotted in an extremely short space of time.

What is claimed is:

1. In an automatic telephone exchange system, a main group of automatic switches, said main group of automatic switches being divided into sub-groups, an allotter switch individual to said main group of automatic switches, an allotter switch individual to each of said sub-groups, means to determine which of said switches shall be taken for use as a result of the cooperation of said main group allotter switch and one of said sub-group allotter switches and means to advance said main group allotter each time that a switch is taken for use.

2. In an automatic telephone exchange system, a main group of automatic switches, said main group of automatic switches being divided into sub-groups, a control switch individual to said main group of automatic switches, a control switch individual to each

of said sub-groups, means to control certain operations of said automatic switches as the result of the cooperation of said main group control switch and one of said sub-group control switches, means to bring said sub-group control switches successively into cooperation with said main group control switch, and means to advance said main group control switch each time that a control of one of said automatic switches is effected.

3. In an automatic telephone exchange system, a plurality of control switches, a master control switch, a plurality of automatic switches, a controlling circuit for operating said automatic switches, means responsive to the operation of said control switches for preparing a portion of said controlling circuit, means including said master control switch to render said controlling circuit effective and means to advance said master control switch each time that a controlling circuit is made effective.

4. In an automatic telephone exchange system, a plurality of group allotter switches, a master allotter switch, automatic switches controlled by said allotter switches and arranged in groups, means to operate said group allotter switches to pre-allot an automatic switch in each group when there is a switch in such group in condition for allotment, means under the control of said master allotter to render said pre-allotment effective to put an automatic switch into use, means to advance said master allotter into cooperative relation with the group allotter of a new group each time that a switch is taken for use, and means to bring said master allotter to rest in cooperative relation with a group allotter only when there is a switch in such group available for use.

5. In an automatic telephone exchange system, a plurality of group allotter switches, a master allotter switch, automatic switches controlled by said allotter switches and arranged in groups, means to operate said group allotter switches to preallot an automatic switch in each group, means under the control of said master allotter to render said preallotment effective to put an automatic switch into use, and means to advance said master allotter into cooperative relation with the group allotter of a new group each time that a switch is taken for use.

6. In an automatic telephone exchange system, a main group of automatic switches, said main group of automatic switches being divided into sub-groups, a control switch individual to said main group of automatic switches, a control switch individual to each sub-group of automatic switches, means to control certain operations of said automatic switches as the result of the co-operation of said main group

control switch and one of said sub-group control switches, and means to advance said main group control switch into cooperative relation with the control switch of a new 5 sub-group each time that an automatic switch reaches a certain stage of operation.

7. In an automatic telephone exchange system, a main group of automatic switches, said main group of automatic switches being divided into sub-groups, a control switch individual to said main group of automatic switches, a control switch individual to each sub-group of automatic switches, means to control certain operations of said automatic 10 switches as the result of the cooperation of said main group control switch and one of said sub-group control switches, means to bring about such cooperation only when there is at least one automatic switch in a 15 sub-group in a certain condition, and means to advance said main group control switch each time that a control of one of said automatic switches has been effected.

8. In an automatic telephone exchange system, a plurality of control switches, a master control switch, automatic switches controlled by said control switches, controlling circuits for operating said automatic switches, means under the control of said 20

control switches for preparing portions of 30 said controlling circuits, means under the control of said master control switch to render said controlling circuits successively effective, and means to advance said master control switch each time that a controlling 35 circuit is made effective.

9. In an automatic telephone exchange system, a group of multiple terminals, a group of automatic switches having common access to said multiple terminals, said group of automatic switches being arranged 40 in sub-groups, means to allow one only of said group of automatic switches to be in position to be started at a given time, a control switch individual to said main group 45 of switches, a control switch individual to each sub-group of switches, means under the control of said main group control switch and said sub-group control switches to determine the order in which said switches are 50 moved into a position to be started, and means to advance said main group control switch each time that one of said automatic switches is started.

In witness whereof, I hereunto subscribe 55 my name this 19th day of May, A. D. 1919.

ALBEN E. LUNDELL.
